CLAIM

The ornamental design for an earbud, as shown and described.

DESCRIPTION

FIG. 1 is a front view of an earbud for the left ear according to this disclosure;

FIG. 2 is a back view of the earbud of FIG. 1;

FIG. 3 is a left side view of the earbud of FIGS. 1 and 2;

FIG. 4 is right side view of the earbud of FIGS. 1-3;

FIG. 5 is a top view of the earbud of FIGS. 1-4;

FIG. 6 is a perspective view from the left, front, and below of the earbud of FIGS. 1-5;

FIG. 7 is a perspective view from the front, right, and below of the earbud of FIGS. 1-6;

FIG. 8 is a perspective view from the front, right, and above of the earbud of FIGS. 1-7;

FIG. 9 is a perspective view from the left, front and above of the earbud of FIGS. 1-8; and,

FIG. 10 is a bottom view of the earbud of FIGS. 1-9.

FIGS. 1-10 show a first embodiment for a left-sided earbud; a second embodiment for a right-sided earbud, which is a mirror image of the preceding embodiment, is also claimed but not shown. Any broken lines shown are included for the purpose of illustrating portions of the earbud that form no part of the claim. The shading lines in the drawings show contour and are not intended to indicate surface orientation.

1 Claim, 5 Drawing Sheets
